UNITED STATES PATENT OFFICE.

MARION F. HUDSON, OF POPLAR BLUFF, MISSOURI.

REFRIGERATOR.

1,191,309.

Specification of Letters Patent. Patented July 18, 1916.

Application filed July 10, 1915. Serial No. 39,072.

To all whom it may concern:

Be it known that I, MARION F. HUDSON, a citizen of the United States, residing at Poplar Bluff, in the county of Butler and 5 State of Missouri, have invented certain new and useful Improvements in Refrigerators, of which the following is a specification, reference being had to the accompanying drawings.

10 This invention relates to an improved refrigerator and has for its primary object to provide means for maintaining the provision chamber of the refrigerator at a very low temperature with a minimum consumption of ice.

15 The invention has for a more particular object to provide a refrigerator having a provision compartment, the walls of which are spaced from the body walls of the refrigerator, a porous water conductor arranged upon the walls of the provision compartment and upon which the ice is adapted to be placed, the walls of the provision compartment having openings therein, over 20 which the water is carried by said porous conductor.

25 The invention has for a further general object to improve and simplify the construction of refrigerators and provide means for maintaining the interior of the refrigerator at a low temperature and also avoid the possibility of entrance of drainage water from the ice, to the provision compartment of the refrigerator.

30 With the above and other objects in view, my invention consists in the novel features of construction, combination, and arrangement of parts to be hereinafter more fully described, claimed, and illustrated in the 35 accompanying drawing, in which,

Figure 1 is a side elevation of a refrigerator, constructed in accordance with the preferred embodiment of the invention, the door thereof being open; Fig. 2 is a vertical 40 section taken on the line 2-2, of Fig. 1; Fig. 3 is a section taken on the line 3-3, of Fig. 2.

45 Referring in detail to the drawing, 5 designates the body of the refrigerator, which may be of any desired size and proportions. The body walls may, if preferred, be suitably insulated in any well known manner. The base or bottom wall 6 of the body of the refrigerator is provided in one 55 corner with an opening, indicated at 7, to which a suitable drain pipe 8 is adapted to

be connected. The top of the refrigerator body is closed by means of a cover, indicated at 9 and the front wall of the refrigerator has an opening, to provide access to the provision compartment hereinafter referred to and this opening is closed by means of a suitable door, as shown at 10.

11 designates the rear wall and 12 the side walls of the provision compartment. These 60 walls, it will be observed, are spaced from the corresponding walls of the refrigerator body and the bottom wall 13 of this provision compartment is also spaced from the bottom wall 6 of the refrigerator while the 65 top wall 14 is disposed at a point below the upper open end of the refrigerator. The top, bottom and side walls of the provision compartment are soldered or otherwise secured upon the inner face of the front wall 70 of the refrigerator, around the edges of the door opening therein.

75 In the rear wall 11 of the provision compartment, a plurality of obliquely inclined slots 15 are provided and narrow, outwardly 80 projecting flanges 16 extend along the longitudinal edges of these slots. In the side walls 12 of the provision compartment, a series of circular openings 17 are formed by punching the metal outwardly. Upon the 85 inner faces of the side walls 12, the spaced supporting flanges 18 are secured, upon which the trays 19 are mounted. These trays are also provided in their side and rear upstanding walls with openings 20 which 90 are adapted to coincide with the openings in the side walls of the provision compartment and the slots of the rear wall thereof, when the trays are in position.

95 Upon the provision compartment within the body of the refrigerator, a sheet or cover of fabric or other porous material 21 is adapted to be arranged. This cover extends over the top and side and rear walls of the provision compartment. This fabric 100 sheet extends the entire length of the provision compartment. Metal plates 22 are hingedly mounted at their outer longitudinal edges, as indicated at 23, upon the side and rear walls of the refrigerator body and normally extend inwardly and downwardly at an inclination and rest at their free edges upon the fabric cover 21. Upon the latter edges of these plates, the block of ice is adapted to rest and several bottles and other 105 like commodities may be placed upon these supporting plates in immediate juxtapo-

sition to the ice. The hinged plates 22 may be readily raised to a vertical position in parallel relation to the refrigerator walls when it is desired to arrange the fabric wa-
5 ter conducting sheet 21 in place or remove the same. The free edges of these plates also exert a pressure upon the fabric sheet by reason of the ice block resting thereon so that an excess of water and waste thereof can-
10 not flow downwardly over the fabric walls, but the water will seep slowly through the porous material and past the slots 15 in the walls of the provision compartment.

In the use of the refrigerator, it will be
15 understood that the water from the melting
ice is directed, by the plates 22, upon the
fabric cover sheet by which it is conducted
downwardly around the side and rear walls
of the provision compartment until said
20 fabric sheet becomes thoroughly saturated.
This drainage water, as it passes the slots
or openings in the walls of the provision
compartment, results in a thorough cooling
25 of the air within the provision compartment,
so that the provisions therein will be prop-
erly preserved. The water soaking through
the cloth or fabric covering collects in the
bottom of the refrigerator and finally passes
30 off to the drain pipe 8. It will be under-
stood that the front door of the refrigerator
is opened occasionally to renew the interior
air after the pad or fabric has become satu-
rated so that the process of evaporation will
continue.

35 From the above description, taken in con-
nection with the accompanying drawings,
it is thought that the construction and man-
ner of use of my improved refrigerator will
be clearly understood. It will be obvious
40 that by reason of the cooling cloth for the
walls of the provision compartment, the full
refrigerating effect of the ice is obtained
and a compartment of comparatively large
45 size may be maintained at a low tempera-
ture and for a maximum length of time,
with a relatively small quantity of ice. The
flanges 16, surrounding the slots in the wall
of the provision compartment, effectively
50 prevent the entrance of water to the in-
terior of the compartment. By reason of the
inclination of these slots, the water will be
properly conducted by the flanges and dis-

charged upon the exterior surface of the
wall. My improved refrigerator is quite
simple in its construction, highly effective 55
and reliable in practical use, and can be
manufactured at considerably less cost than
the ordinary refrigerator which is provided
with complicated means for insulating the
interior of the provision compartment of 60
the refrigerator.

While I have shown and described the
preferred construction and arrangement of
the several structural features of my invention,
it is to be understood that the same is 65
susceptible of considerable modification
therein and I, therefore, reserve the privi-
lege of resorting to all such legitimate
changes as may be fairly embodied within
the spirit and scope of the invention as 70
claimed.

What is claimed, is:—

1. In a refrigerator, a body, a provision
compartment having its walls spaced from
the body walls of the refrigerator, the rear 75
wall of said compartment being provided
with a plurality of spaced obliquely in-
clined slots and flanges projecting out-
wardly from the longitudinal edges of each
80 slot, a porous sheet arranged upon the top 85
of the provision compartment and hanging
loosely over the rear wall in contact with
said flanges, and metal plates hinged upon
the refrigerator walls and resting at their
free edges upon the porous sheet which is 90
disposed over the top of the provision com-
partment, said free edges of the hinged
plates being pressed downwardly by an ice
cake engaged thereon.

2. In a refrigerator, a body, a provision 90
compartment having its walls spaced from
the body walls of the refrigerator, a remov-
able fabric cover arranged upon the walls
of the provision compartment, and metal
95 plates hinged along one of their longitudinal
edges to the side and rear walls of the re-
frigerator body and resting at their other
free edges upon said fabric cover.

In testimony whereof I hereunto affix my
signature in the presence of two witnesses. 100

MARION F. HUDSON.
